(57) **CLAIM**

The ornamental design for a holding pad for carrying substrate, as shown and described.

DESCRIPTION

FIG. 1 is a front view of a holding pad for carrying substrate showing our new design;

FIG. 2 is a rear view thereof;

FIG. 3 is a top plan view thereof;

FIG. 4 is a bottom view thereof;

FIG. 5 is a right side view thereof;

FIG. 6 is a left side view thereof;

FIG. 7 is a front perspective view thereof;

FIG. 8 is a rear perspective view thereof; and,

FIG. 9 is a cross-sectional view taken along the line 9-9 in FIG. 1.

The broken lines depict unclaimed portions of the holding pad for carrying substrate, and thus form no part of the claimed design.

1 Claim, 9 Drawing Sheets
